(57) **CLAIM**

The ornamental design for a long arm gun holder, as shown and described.

DESCRIPTION

FIG. 1 is a side elevational view showing my new design of a long arm gun holder with an illustrative gun in phantom outline;

FIG. 2 is a perspective view;

FIG. 3 is a right side elevational view which is a mirror image of the left side;

FIG. 4 is a front elevational view;

FIG. 5 is a rear elevational view;

FIG. 6 is a top plan view; and,

FIG. 7 is a bottom plan view.

The broken line drawing of a long arm gun is for illustrative purposes only and form no part of the claimed design.
